W. Mauds' Design
for a Spoon.

John R. Mauds,
Inventor.

Dec. 1580

John R. Menett, of New York, N. Y.
Letters Patent No. 1580, dated May 13, 1862,

The schedule referred to in these Letters Patent and making part of the same.

To all whom it may concern:

Be it known that I, John R. Menett, of the City, County and State of New York, have produced a new and ornamental Design for Spoons; and I do hereby declare that the following is a full, clear and exact description of the same, reference being had to the accompanying drawing forming a part of this specification, in which

Figure 1, represents a side elevation of my design,

Figure 2, is a plan or top view of the same,

Similar letters of reference in both views indicate corresponding parts.

The bowl A, of my spoon is made in the usual form and shape and it connects with the handle B, in the ordinary manner.

The shank of the handle where it joins the bowl is ornamented by two volutes a, between which an obtuse spear point b, is visible.

Des. 1580

From the volutes a, two bars c extend parallel to each other, to the rosette d, which occupies a central position on the shank of the handle. The bars c, are separated from each other by a central crease e, and they run along close on the edges of the shank. The rosette d, is ornamented by a flower occupying nearly its entire surface.

The bars c, which are interrupted by the rosette d, continue from the pane up to a flat band f, which surrounds the shank of the handle and which is joined by a similar band h.

From this band three leaves i, j, k, emanate which are arranged in the form of a belt, their roots being apparently tied together by the bands f and h, and the points of the outer leaves i and k, being turned out in the shape of volutes whereby the rim of the belt is represented. This belt supports an antique medal C, which forms the principal point of novelty in my design. This medal consists of a flat oval rim l, surrounding a cavetto m of the same oval shape and forming in conjunction with this cavetto the frame of the medal. The space surrounded by this frame is ornamented by a head n, and a semi-spherical projection o, secured to the outer end of the medal C, completes the handle.

The several ornaments on the handle B, give to the pane a rich and pleasing appearance, and it is particularly the medal C, which renders the look of my spoon novel and unique.

Having thus fully described my design, what I claim as new and desire to secure by Letters Patent, is

The handle B, of a spoon when the pane is ornamented with an antique medal C, as specified; also the belt i, j, k, bands f, h, rosette d, bars c, and volutes a, all as shown and described.

Witnesses,

E.S. James Laird. }
G.W. Hodgson. }

Mr. R. Venett,
